ICE STUD FOR SNOWMOBILE TRACKS

Roger G. Janssen, Rte. 2, Crookston, Minn. 56716, and
Wayne G. Schantzen, 201 S. Crocker, Thief River
Falls, Minn. 56701

Filed May 6, 1974, Ser. No. 467,019

Term of patent 14 years

Int. Cl. D12—14

U.S. Cl. D12—7

FIG. 1

FIG. 2

FIG. 4

FIG. 3

FIG. 5

FIG. 1 is a perspective view of an ice stud for snowmobile tracks showing our new design;

FIG. 2 is a top plan view thereof;

FIG. 3 is a bottom plan view thereof;

FIG. 4 is a side elevational view thereof; and

FIG. 5 is a sectional view taken along the line 5—5 in FIG. 2.

We claim:

The ornamental design for an ice stud for snowmobile tracks, substantially as shown.
